UNITED STATES PATENT OFFICE

ARTHUR H. DIERKER, OF COLUMBUS, OHIO

GRINDING MACHINE

Application filed April 15, 1929. Serial No. 355,151.

This invention relates to an improved mixer or grinder, and has for an outstanding object the provision of a mixing or grinding appliance wherein the materials undergoing treatment may be continuously introduced into and removed from the shell of the appliance. The device may also be used as a batch mill as well as one of a continuous nature.

It is another object of the invention to provide a mixer or grinder which comprises generally a rotatable shell of cylindrical form into which the materials to be treated are led and to provide within the shell a roll of smaller diameter than the internal diameter of the shell and wherein the roll is so mounted and constructed as to provide for an efficient rubbing or kneading effect on the materials under treatment to the end of bringing such materials, upon the rotation of the shell, into effective engagement with one another and in repeated contact to provide either a thorough mixing, rubbing, kneading or reduction action.

It is another object of the invention to construct the roll so that it is of shorter length than the material receiving chamber of the shell and also to mount the roll within the shell in a substantially fixed position, this fixed position being varied to suit the material being treated, whereby during the rotation of the shell the materials under process of mixing or reduction travel in cyclic paths, first, between the inner wall of the shell and the outer peripheral wall of the roll, second, into intimate contact with other individual particles of the material or materials under treatment, and third, are permitted to return to a normal or starting position by moving past the ends of the roll and dropping to the bottom of the shell, wherein the materials again work upwardly between the shell and the roll to repeat the cycle.

The operation of this mill is best shown by its action on molding sands. In making a synthetic molding sand, quartz sand of a suitable grain size is mixed with a plastic bonding material and then subjected to a kneading and rubbing action which coats each grain with a proper amount of plastic, co-

hesive material to form an aggregate of a plastic, refractory nature suitable for making molds for metal castings. The mill or mixer comprising the present invention, gives the necessary mixing and kneading action for the making of these sands. After continued use, the bonding material in molding sands loses its plastic nature and becomes an undesirable encrustation on the quartz grains. In the reclaiming of foundry sands, it is necessary to loosen this encrusted material from the grains without crushing the grains themselves. This loosening is best accomplished by a rubbing and kneading action such as is provided by the mill herein-after described.

For a further understanding of the invention reference is to be had to the following description and the accompanying drawings, wherein:

Figure 1 is a view in end elevation of the continuous mixing or grinding machine comprising the present invention;

Figure 2 is a side elevation thereof;

Figure 3 is a vertical longitudinal sectional view taken through the machine on the line 3—3 of Figure 1;

Figure 4 is a diagrammatical view illustrating the action of a loosely mounted roll in a rotating shell, and

Figure 5 is a similar view illustrating the action of a positively positioned roll.

Referring more particularly to the drawings, the numeral 1 designates my improved mixing or grinding machine in its entirety. In its preferred form the machine comprises a base 2 provided with spaced upstanding webs 3 employed to support rollers 4 arranged to serve as a cradle for the reception of a rotatable cylinder or shell 5. The ends of the cylinder are equipped with annular rails 6 which engage with the flanged wheels or rollers 4 in order to provide for the anti-friction support and rotation of the cylinder. Fixed to the cylinder and surrounding the same at a position between the annular rails is a gear 7 which is adapted to engage with a pinion (not shown) driven by a suitable source of power for effecting rotation of the cylinder about its longitudinal axis.

The cylinder is closed at one end by a stationary head 8 provided with an enlarged axial opening 9, the opposite end of the cylinder being closed by a similar head 10 which also includes an axial opening 11 and is provided with a flanged lip 12. Materials are preferably introduced into the shell or cylinder by way of the opening 9 and are discharged through the opening 11.

Pivotedly mounted, as at 13, upon each end of the base 2 are bell crank levers 14. To the arms 14^a of these levers there are secured the opposite ends of a longitudinally extending shaft 15 which passes through the cylinder 5 in a position eccentric to the axis of said cylinder. Within the cylinder the shaft 15 is provided with fixed spaced arms 16, carrying at their outer ends a longitudinally extending shaft section 17 around which is journaled for rotation a roll 18. Similarly there is mounted on the shaft 15 a longitudinal quill or sleeve 19 which carries fixed longitudinally spaced arms 20 corresponding in function to the arms 16. The outer ends of the arms 20 carry a shaft section 21 which receives a roll 22, similar in function and position to the roll 18. The rolls 18 and 22 are spaced longitudinally in the cylinder or shell 5, the interior of the latter being provided with an annular partition 23 which divides the shell into primary and secondary compartments 24 and 25 respectively. The partition 23 is formed with an adjustable door 26 permitting the materials released from the compartment 24 to pass into the compartment 25 and after being treated in said latter compartment the materials are discharged from the machine by way of the outlet chute 27.

To maintain the rolls 18 and 22 in the desired operating positions the shaft 15 and the sleeve 19 at a point exterior of the cylinder 5 are equipped with fixed arms 28. The outer ends of these arms are slotted to receive upwardly standing bolts 29 carried by the base 2. Surrounding the bolts 29 positioned by the ends of the arms 28 and the base 2 are coil springs 30. These springs normally serve to maintain the arms 28 in engagement with nuts or other stop devices 31 carried by the upper ends of the bolts 29, thus positively positioning the rolls 18 and 22 in desired positions within the shell. However, if the roll should encounter materials of excessive thickness relief is provided through the medium of the springs 30 which operate to allow limited relief movement of the rolls. Also by means of the threaded adjustments 32 of the springs 30 the intensity of action on the materials may be determined. Furthermore, the springs 30 serve to maintain the rolls in positive engagement with the materials under treatment in the shell but in spaced relation from the walls of the cylinder 5. The shorter arms of the bell cranks 14 are formed with

transversely projecting bolts 33 which operate in arcuate slots 34 provided in the sides of the base 2 and which operate as guides or braces in suspending the rolls in their desired positions of operation in the shell. If desired the roll 22 in the primary compartment 24 may be formed with cleats 35 for breaking down lumpy materials or large lumps that would not ordinarily be reduced between the smooth walls of the roll and shell.

In operation, the materials to be treated, for example foundry sands, are continuously introduced into the primary compartment 24 of the cylinder. The operation of the machine on such materials has been shown diagrammatically in Figure 5 wherein it will be observed that due to the length of the roll 22 and its position in the shell, the sand will follow the paths of movement indicated by the continuous arrow A. The position of the material being treated is secured by the rotation of the cylinder or shell in the direction indicated by the arrow B and due to frictional contact between the walls of the cylinder and the loose material positioned therein, the said materials are located in the main to one side of a vertical plane passing through the axis of the cylinder. As the cylinder revolves these materials then follow the paths of movement indicated at A, being first moved upwardly between the roll 22 and the walls of the cylinder and then after passing said roll the material moves upwardly to a limited extent but is returned to the bottom of the cylinder by gravitating downwardly past the end or ends of the roll 22. This produces a continuous action of a rubbing, reducing or mixing character on the materials undergoing treatment, and this action may then be repeated as the materials pass into the secondary compartment 25 wherein they receive similar treatment through the provision of the roll 18, and from the secondary chamber the materials are discharged in a finished condition from the machine.

If the rolls 18 and 22 were not fixed, as shown in Figure 5, but were loosely mounted in said cylinder, as shown in Figure 4, the materials undergoing treatment would have a tendency to bunch or collect on one side of the roll indicated at C in Figure 4, thus reducing the efficiency of the machine. However, I have found that by definitely positioning the rolls, as shown in Figure 5, and by using a roll of smaller length than the chamber or compartment in which it is situated for operation, a greatly improved reducing or mixing action is obtained and a machine of marked efficiency provided.

Although only two rolls have been described and shown, it will be understood that one or more than two rolls may be employed, the number used being dependent on the type

and amount of work required on the particular material being treated.

What is claimed is:

1. In a machine of the character described, a base, a cylinder mounted for rotation about its longitudinal axis and supported by said base, said cylinder having material receiving and discharging openings formed in the opposite ends thereof, a shaft passing through said cylinder and supported by said base, a pair of arms fixed to said shaft, and a roll rotatably carried by the outer ends of said arms and arranged immediately contiguous to one of the walls of said cylinder. 10
2. In a machine of the character described, a base, a cylinder mounted for rotation about its longitudinal axis and supported by said base, a supporting member carried by said base and arranged within said cylinder, a roll carried by the outer portion of said supporting member and disposed immediately adjacent to the inner wall of said cylinder, and means normally serving to maintain said roll and its supporting member within a predetermined position within said cylinder. 15
3. In a machine of the character described, a base, a cylinder mounted for rotation about its longitudinal axis and supported by said base, a pair of pivoted levers carried by said base and arranged at the opposite ends of said cylinder, a shaft carried by said levers and extending longitudinally through said cylinder, a pair of arms fixed to said shaft and disposed within said cylinder, a roll rotatably carried by the outer ends of said arms and positioned immediately adjacent to the inner wall of said cylinder, and spring means cooperative with said shaft for maintaining said roll in a predetermined position within said cylinder. 20
4. In a machine of the character described, a base, a cylinder having the opposite ends thereof provided with material receiving and discharging openings, means carried by said base for effecting the rotatable support of said cylinder thereon, a pair of levers carried by said base, a shaft connected with the outer ends of said levers and extending longitudinally through said cylinder, arms fixed to said shaft in longitudinally spaced order and arranged within said cylinder, a roll carried by the outer ends of said arms and disposed immediately adjacent to the inner wall of said cylinder, another arm fixed to said shaft exteriorly of said cylinder, and spring means cooperating with said last named arm and serving to maintain said roll in a predetermined region of operation within said cylinder. 25
5. In a machine of the character described, a base, an open ended cylinder mounted for rotation about its longitudinal axis and supported by said base, a pair of levers pivotally mounted on said base and disposed at the opposite ends of said cylinder, a shaft carried by the outer ends of said levers and arranged to extend longitudinally through said cylinder, spaced supports fixed to said shaft, rolls carried by said supports and arranged immediately contiguous to the side walls of said cylinder, and spring means cooperative with said supports for maintaining said rolls in predetermined regions of operation within said cylinder. 30
6. In a machine of the character described, a base, a cylinder mounted for rotation about its longitudinal axis and supported by said base, a supporting member carried by said base and arranged within said cylinder, a roll carried by the outer portion of said supporting member and disposed immediately adjacent to the inner wall of said cylinder, and yieldable means for maintaining said roll in pressure contact with the material under treatment. 35
7. In a machine of the character described, a base, an open ended cylinder mounted for rotation about its longitudinal axis and supported by said base, a pair of levers pivotally mounted on said base and disposed at the opposite ends of said cylinder, a shaft carried by the outer ends of said levers and arranged to extend longitudinally through said cylinder, spaced supports fixed to said shaft, a roll carried by and journaled for rotation at the outer ends of said supports, said rolls being arranged immediately contiguous to the side walls of said cylinder, adjustable means formed with said base and levers for maintaining the latter in various adjusted positions, yieldable means for maintaining said roll in pressure contact with the material under treatment, and means for effecting the adjustment of said yieldable means. 40
8. In a machine of the class described, a base, an open ended cylinder mounted for rotation about its longitudinal axis and supported by said base, a pair of bell cranks pivotally mounted on said base and disposed at the opposite ends of said cylinder, a shaft carried by the upper ends of said bell crank and arranged to extend longitudinally through said cylinder, an adjustable connection between said base and the lower ends of said bell cranks, spaced supports carried by said shaft, a roll carried by said supports and arranged immediately contiguous to the side walls of said cylinder, an arm fixed to said shaft exteriorly of said cylinder, and spring means connecting said arm and base and serving to maintain said roll in pressure contact with the material under treatment. 45
9. In a machine of the character described, a base, a cylinder mounted for rotation about its longitudinal axis and supported by said base, a pair of levers pivotally and adjustably carried by said base, said levers being arranged at the opposite ends of said cylinder, a shaft carried by and journaled in the upper ends of said levers, a pair of arms fixed to said 50
- 60
- 65

- shaft, a roll rotatably carried by the outer ends of said arm, a sleeve carried by said shaft, a pair of arms fixed to said sleeve, a roll carried by the outer ends of said arm, and spring means cooperating with said shaft and sleeve for maintaining said roll in pressure contact with the material under treatment, the spring means co-operating with the shaft being independent from the spring means co-operating with said sleeve.
10. In a machine of the character described, a base, an open ended cylinder mounted for rotation about its longitudinal axis and supported by said base, said cylinder being divided into two chambers by a transversely arranged partition, said partition being formed with an opening for the passage of the material from one chamber to the other, a pair of levers carried by said base and situated at the opposite ends of said cylinder, a shaft carried by the outer ends of said levers and arranged to extend longitudinally through said cylinder, spaced sets of supports carried by said shaft, rolls carried by the outer ends of said supports and arranged one in each of said chambers, said rolls being disposed immediately adjacent to the inner wall of said cylinder and having their ends spaced from the end walls of said chambers, and means co-operating with said rolls for maintaining the latter in pressure contact with the material under treatment.

11. In a machine of the character described, a base, a cylinder mounted for rotation on said base, said cylinder having material receiving and discharging openings formed in the opposite ends thereof, a transversely arranged partition within said cylinder for dividing the latter into a pair of chambers, means formed with said partition for positively advancing the material from one chamber to the other, a shaft passing through said cylinder and supported by said base, spaced sets of supports carried by said shaft, rolls carried by the outer ends of said supports and arranged one in each of said chambers, and pressure means for maintaining said rolls in predetermined regions of operation within said cylinder.

50. In testimony whereof I affix my signature.
ARTHUR H. DIERKER.
